UNITED STATES PATENT OFFICE.

WILLIAM L. L. PIERCE AND WILLIAM J. PIERCE, OF SAN FRANCISCO,
CALIFORNIA.

ELECTRO-THERAPEUTIC BELT.

SPECIFICATION forming part of Letters Patent No. 371,356, dated October 11, 1887.

Application filed March 11, 1887. Serial No. 230,559. (No model.)

To all whom it may concern:

Be it known that we, WILLIAM L. L. PIERCE and WILLIAM J. PIERCE, citizens of the United States, residing in the city and county of San Francisco, and State of California, have invented certain new and useful Improvements in Therapeutic Belts; and we do hereby declare that the following is a full, clear, and exact description of our said invention, reference being had to the accompanying drawings, that form a part of this specification.

Our invention relates to improvements in therapeutic belts which are composed of a number of galvanic elements joined together in belt form and with the poles connected to exposed plates, disks, or electrodes that are adapted to be brought in contact with the body of the wearer.

Our improvements in respect thereof consist in producing an element for batteries of this character by bending up and folding together plates or strips of dissimilar metals in the novel manner hereinafter described and in uniting a number of these elements by links or couplings in such manner that each link connects unlike metals between one element and its neighbor; also, in a peculiar construction of carrying-belt and fastenings adapted to support the battery and having certain features of adjustability and reversibility by which the battery may be adjusted to be in direct contact with the body or be worn with the belt interposed between the battery and the person; also, in the combination, with a battery formed of coupled elements, as described, of electrodes and reversible connections by which the character of the current can be changed, as desired, and either the positive or negative current be directed and brought to either electrode.

The following description fully explains the nature of our said improvements and the manner in which we construct, apply, and carry out the same to produce an improved belt, the drawings being referred to by figures and letters.

Figure 1 is a perspective view of a belt constructed according to our invention, the front strap being broken away to expose parts that would be covered in the view. Fig. 2 shows

in side view a portion of the supporting-belt at one end. Fig. 3 shows an edge view of the same. Fig. 4 is a longitudinal section through view Fig. 2, taken on a center line through x x . Figs. 5, 6, 7, 8, and 9 illustrate the construction of the battery elements, Fig. 5 being an edge view of an element in complete form; Fig. 6, a perspective view of the element partly folded into form; Figs. 7 and 8, views of the two plates of dissimilar metal partly bent into shape before being placed together; Fig. 9, a section longitudinally through the plates after they are laid together preparatory to being folded into shape.

The carrying-belt A is formed of inelastic material—such as webbing or similar fabric—and is provided with supporting-loops B B^2 on both sides or faces and at points in front and at the back, through which the metallic belt or battery proper is slipped, as seen in Fig. 1. At the front and just back of each end of the webbing belt is fastened, by lines of stitching c c , an elastic strap, D, provided with a buckle, D^2 , on the outer end and a ring or loop, D^3 , on the opposite end. In the belt, at a point about in line with or near to this loop end, is a re-enforced eyelet-hole, E, large enough to allow a hook or catch with which the end of the battery-belt is furnished to be passed through and take the loop. The battery composed of the coupled elements G is of such length that its two ends connect directly to the ends of the elastic straps D, and by means of the metallic hooks H H^2 , to which are attached the end elements, the loops D^2 form the terminals of the battery when the hooks are sprung into these loops.

By providing the eyelet holes E at the points indicated the battery can be shifted from the outside to the inside of the webbing belt to bring it directly in contact with the body of the wearer, as it will be seen that by passing the hook H on the end of the battery-belt out through the hole E connection is readily made with the elastic strap D. Figs. 2 and 3 illustrate the position of the parts and fastenings when the battery is placed on the inside of the webbing belt. The battery is therefore kept properly stretched or at a suitable tension to preserve connection between one ele- 100

ment and the next, by virtue of the elastic straps D, in one position as well as the other, and with the same fastenings and connections. Between the outer ends of the two elastic straps 5 an elastic strap, I, completes the supporting-belt and forms the means for tightening it around the body, as well as for adjusting it to different sizes of waist.

The electrodes N and P are metal disks 10 loosely attached by hooks k to the webbing belt at the back and to the elastic strap I at the front. Each one is connected with its end of the battery, the one N with the negative and the other, P, with the positive end by an 15 insulated wire cord, L or L^x. These cords have spring-hooks m m^x on the ends, and are connected by them to the loops D² or the hooks H, which constitute the terminals of the metallic belt. To change the direction of the 20 galvanic current, therefore, and reverse the electrodes it is only necessary to detach the cords at the ends m and m^x and connect them to opposite terminals, bringing the cord L, Fig. 1, for instance, from the left-hand end of 25 the battery over to the right-hand end and changing the cord L^x in the same manner.

The manner in which we construct the element G will be clearly understood by referring to Figs. 6, 7, 8, and 9 of the drawings. 30 It is composed of two strips of dissimilar metals separated from metallic contact by a strip of felt or flannel. The two metal strips, when laid together, are bent and folded in such a peculiar manner that loops or knuckles are formed 35 to take coupling-links, and these, as well as the plates, are firmly held and secured without solder and without the use of fastenings of any kind. The strip g, forming the outer plate of the element, is cut somewhat longer than the strip h, that sets inside, to allow for flaps g² and g^x at the ends. These are bent back upon the strip and in the same side, as shown in Figs. 7 and 9, and the one g² is also formed at the 40 bend into a loop or knuckle, like the loop of a hinge, to take around the link R. The two metal strips g h are cut of the same width, but the one h is somewhat shorter, to fit in between the turned-over ends of the outer plate. Before it is laid to the plate g the flannel s is 45 placed upon the strip and its ends are turned over the metal at both ends to properly insulate the strip at those points where the outer strip overlaps it. These three parts g h s thus laid together are then bent over at the line a (see Fig. 9) to form the hook end g³, and then again at the line b to complete the desired 50 shape. When constructed in this manner, each element has a link permanently but loosely confined at one end and a hook at the opposite end. A number of elements are then 55 readily coupled together by setting the hook end of one through the link of the next ele-

ment, so that the link rests in the bend of the plates. By this means the plates are held without fastenings of any kind and the elements are joined together in a strong and durable manner. 65

The whole construction is simple and does not require any preparation or getting out of the plates or blanks by machinery; neither are 70 there any pins or screws to work loose or soldered joints to break.

Having thus fully described our invention, what we claim, and desire to secure by Letters Patent, is—

1. In a galvanic belt, the combination, with the metallic belt or battery composed of coupled elements, of the supporting-belt A, having carrying-loops on both sides, and the elastic straps D D, with buckles and metallic loops or connections D² D² and having the holes or openings through it at the front, as described. 75

2. The non-elastic supporting-belt for a galvanic battery, consisting of the non-elastic webbing belt A and the elastic straps D D, provided with buckles and metallic connections D² D² on the inner ends and having the loops on the inside and the outside and the holes or apertures, as described. 85

3. In combination with the battery formed 90 of loosely-coupled elements, as described, the inelastic or webbing belt A, the elastic straps D D, secured at or near its ends, the coupling-strap I, the loops D² D² on the straps D, and the hooks on the terminals of the battery. 95

4. In combination with the battery composed 100 of coupled elements, as described, and a non-conducting supporting-belt, the disks N P, suspended from the non-conducting belt, and the conducting-cords L L^x, each connected to its disk at one end and to the terminals of the battery at the other end by hooks or metallic detachable connections.

5. A galvanic element for batteries of the character described, consisting of the plates g 105 h, of dissimilar metals, separated by the insulating strips s and laid together and bent or folded, substantially as specified, to form the loop at one end and the bend at the other end. 110

6. The herein-described galvanic element, 115 formed of strips of dissimilar metals of different lengths with interposed strips of flannel or other suitable material, the outside plate being bent over upon the inner plate at both ends and the two plates folded together, substantially as and for the purpose set forth.

In testimony that we claim the foregoing we have hereunto set our hands and seals.
